Specification of Letters Patent.

Patented Mar. 4, 1919.

Application filed July 6, 1915. Serial No. 38,269.

To all whom it may concern:

Be it known that I, EDWIN E. WAITE, a citizen of the United States, residing at Framingham, in the county of Middlesex and State of Massachusetts, have invented certain Improvements in Needle-Looms, of which the following description, in connection with the accompanying drawings, is a specification, like reference characters on the drawings indicating like parts in the several figures.

This invention relates to looms and is particularly concerned with looms for weaving mechanical fabrics, such as brakelining, straps, and belts, although the invention is usually not limited in its application to this class of goods.

It is the chief object of this invention to devise a machine of the class indicated with which narrow fabrics, and particularly fabrics of the character above mentioned, can be manufactured more economically than with the machines now used for this purpose. A serious difficulty found with the machines now available for manufacturing goods of this class is that their rate of production is very low, due partly to the fact that they are subject to many interruptions and also to the fact that they are so constructed as to be capable of operating only at very low speeds. While the warp supporting and operating mechanism could be run at fairly high speeds, the shuttle can be driven only at a very low speed and consequently the rate of production of the goods is limited to the speed at which the shuttle can be operated. It has been proposed heretofore to overcome this difficulty by inserting the weft in certain classes of goods with a reciprocating needle, hook, or combination of hook and needle, and thus doing away with the shuttle now used for this purpose. In such a machine the weft is laid in double lengths, that is, the weft thread is doubled back upon itself in each shed so that it forms a loop at the side of the shed opposite to that from which it is inserted; and in order to lock the weft against raveling it has been found necessary to use a shuttle arranged to slide through each loop of the weft as soon as it is formed and pull through it a selvage or locking thread in much the same

manner that the shuttle of a lock stitch sewing machine operates to pull a locking thread through the loops of the thread inserted by the needle. While machines of this type, generally known as "needle looms", have found a market in the manufacture of a very limited class of goods, they are not at all adapted to the manufacture of other classes of goods, such for instance, as mechanical fabrics which must be made of coarse thread or yarn. Many reasons for this state of facts will readily suggest themselves to those skilled in this art, one important reason being the fact that a shuttle of a practical size can contain only a relatively short length of coarse thread or yarn and it consequently is necessary to stop the machine very frequently for the insertion of a new bobbin; while, if the shuttle is made large enough to hold a substantially greater amount of yarn, it then becomes necessary to form a very large loop in the weft through which this shuttle can slide and the time saved in inserting the weft with a needle is lost in the take up motion necessary to pull up this large loop of weft.

The present invention relates to needle looms and has for its general object to devise a thoroughly practical machine of this type, adapted especially to weave narrow fabrics. The invention involves both improvements in the general organization of machines of this type and also novel means for locking the loops of the weft at the selvage edge of the fabric. It has been proposed heretofore to use a reciprocating hook or needle for locking the weft loops against raveling, but these machines have never, so far as I am aware, proved satisfactory. The present invention involves features by which the difficulties heretofore experienced in performing the weft locking operation by means of loops or needles have been overcome. These features relating particularly to the supporting and operating mechanism for the needle or hook used for this purpose, and to constructions by which the loops are accurately controlled and the dangers of dropping the loops or failing to pick them up is avoided.

The machine shown in the accompanying drawings is designed particularly to manu-

facture a novel fabric disclosed in my Patent No. 1,243,905, granted October 23, 1917, and in which the weft is doubled back upon itself in each shed, forming a loop at one selvage edge of the fabric (as above described), but the loops so formed are interlocked with each other thus making it unnecessary to use an auxiliary selvage thread to lock the weft against raveling.

10 Referring to the drawings,

Figure 1 is a front elevation of a machine embodying this invention, certain parts of the frame being broken away;

15 Fig. 2 is a vertical, sectional view on the line 2—2, Fig. 1;

Fig. 3 is a plan view of the machine shown in Figs. 1 and 2;

Fig. 4 is a plan view of the weft handling instrumentalities;

20 Fig. 5 is another view of the parts shown in Fig. 4 but showing them in a different position;

Fig. 6 is a perspective view of part of the weft inserting needle;

25 Fig. 7 is a view similar to Figs. 4 and 5 but showing the parts in another position;

Fig. 8 is an end elevation of the parts shown in Fig. 5;

30 Fig. 9 is a fragmentary view showing one step in the operation of locking the weft; and

Fig. 10 is an elevation showing a yarn tension device used in the machine.

The machine shown includes a warp holding and operating mechanism which comprises a set of harnesses 2 mounted for vertical reciprocating movement in a suitable part of the machine frame 4. These harnesses, of course, are provided with suitable healds which are not shown here since such a showing is not essential to an understanding of the present invention. The harnesses are operated by a series of cams 6, one cam being provided for each harness 2, and these cams are all mounted on a cam shaft 8 which is supported in bearings secured to the machine frame and is provided at its forward end with a worm wheel 10 that meshes with a worm 12 fast on the main shaft 14 of the machine. A lever shaft 16 is mounted at one side of and parallel to the shaft 8 and carries a series of levers 18. Each of these levers is connected by means of a link to the bottom of one of the harness frames 2 and carries a roll running in a cam groove formed in one of the cams 6. The cams 6 operate through their respective levers to move the harnesses 2 up and down in their guideways and are, of course, timed to give to the harnesses the motions necessary to effect the desired movement of the warp threads and binders. Each cam lever 18 carries a counterbalancing weight 19.

60 The warp, after passing through the harnesses, is led through a reed 20 and then to a cloth beam or roll 22 and under another

roll 24 mounted close to the cloth beam. The reed 20 is mounted on the upper end of a bell crank lever 21 which is fulcrumed on a shaft 26 and carries at its opposite end a roll running in the cam way of a cam 68 fast 70 on the main shaft 14. The cloth beam 22 is fixed to a shaft 30 which lies parallel to the main shaft and is mounted in bearings supporting it above said shaft. Mounted loosely on the shaft 30 is a worm wheel 32 which is driven by a worm 34 mounted on the end of a vertical shaft 35 that is driven by a worm wheel 36 meshing with the worm 12 on the main shaft. A ratchet wheel 38 is fixed to the shaft 30 close beside the worm wheel 32 80 and the latter wheel carries a pawl that normally is held in engagement with the teeth of the ratchet wheel 38 by means of a spring thus compelling the cloth beam 22 to rotate with the worm wheel 32 in a direction enabling the cloth beam to take up the web of cloth and keep it tight. But by releasing the pawl from the ratchet, the cloth beam can then be rotated by hand in the opposite direction to free the web of cloth from it when 90 desired for any reason. The guide roll 24 rotates on a short shaft which is mounted in ways just back of the bearings for the shaft 30 and is normally held in its operative position by pins 40 which can be taken out, 95 thus allowing the roll 24 to be removed whenever it is desired to back off the web of fabric.

The main shaft 14 carries a pulley 42 which is loosely mounted thereon and also 100 has keyed thereto a hand wheel 44 which may be moved axially of the shaft by means of a bell crank lever 46 to carry it into or out of contact with the loose pulley 42. These parts are provided, on their adjacent ends, with 105 friction faces so that they form, in effect, a clutch.

A spool supporting rack (not shown), of course, is provided back of the machine to hold the spools or cones from which the warp threads and binders are unwound by the machine when it is in operation; or the warp threads and binders may be supported in any other convenient manner.

The warp supporting and operating mechanism above described is arranged when the machine is ready for operation to form a shed *s* between the harnesses and the cloth beam. A needle 50, mounted in suitable guides to reciprocate back and forth through the shed, is utilized to insert the weft and is driven by means of an eccentric on the main shaft operating an eccentric strap 52 which is connected to one arm of a bell crank lever 54, the opposite end of said lever being connected by a short link 56 to the needle 50. The weft *w* is led from a spool or cone through a tension device 58, over a roll or yarn guide 60 mounted on the rear end of the needle, and then through 130

a stationary yarn guide 62 to the eye of the needle. Any suitable form of yarn tension may be used, that shown consisting of two rolls which are pressed together yieldingly by a spring and between which the yarn is guided as it is fed forward.

A selvage hook 65 or needle is mounted on the upper end of a bell crank lever 66 which rocks on the shaft 26 and carries on its lower end a roll running in a cam groove of a cam 68 mounted fast on the main shaft 14. The upper end of this lever runs in a slot formed vertically in a guide arm or bracket 70 which is secured to the machine frame and serves to support this lever arm against lateral movement out of its normal or operative position. (See Fig. 8). Mounted between the reed 20 and the cloth beam 22 and just at the end of the shed of the warp are two horizontal guide rods 72 supported by a bracket arm so that they project one above and one below the web of cloth being woven. The reed 20 has a range of movement from the position in which it is shown in Figs. 2 and 8 to the apex of the shed which lies just in front of the guide rods 72; and the hook 65 has a range of movement from the apex of the shed to a point just under the path of the weft needle 50, this movement taking place in substantially a horizontal plane and in a direction substantially parallel to the selvage edge of the fabric. It will be noted that the needle 50 is cut out on its lower side near the point, as best indicated in Figs. 6 and 8, to allow the hook to move under it when both the needle and hook are at the forward limits of their strokes.

Preferably, the hook 65 is supported in a holder which is mounted to have a slight swinging movement about a vertical pivot 78 that is mounted in a bracket 76 secured to the upper end of the lever 66. Two set screws 89 and 90, respectively, mounted in the bracket on opposite sides of an arm 80 which forms part of the holder, serve to limit the movement of the holder in opposite directions, while a spring 92, connected at one end to the arm 80 and at its opposite end to an eye bolt 94 threaded through part of the bracket 76, normally holds the arm 80 in contact with the set screw 90 and thus swings the forward end of the hook 65 away from the selvage edge of the fabric. In the machine shown a hook of the "latch" type is used; that is, the hook is provided with a pivoted latch 96 arranged to swing either into the position shown in Fig. 9 where it closes the opening of the hook, or into an open position as shown in Figs. 5 and 8 where it lies back nearly parallel with the shank of the hook. At a certain point in the forward stroke of the hook 65, this latch strikes a vertical pin 98 which is secured to the guide 70 and holds the latch open at this particular time,

Assuming now that the loom has been "drawn in," that is, that the warp and binders have been arranged in the harnesses and over the cloth beam in the proper manner for the weaving operation, that the weft 70 needle 50 has been threaded in the manner shown in the drawings and that the operation of weaving has been started, the web of cloth being guided between the cloth beam 22 and the rolls 24 with the pins in the member 22 holding the web of cloth tight, the operation of the machine would be substantially as follows: The weft inserting needle 50 is advanced through the shed, as shown in Fig. 4, by its connections with the driving 80 shaft 14, as above described, and at the same time the hook 65 is moved forward toward the weft needle by its driving connections above described. The weft needle carries with it a double strand of weft thread *w*, as 85 shown in Fig. 4, and both the needle and the hook advance until they arrive substantially in the positions in which they are shown in Figs. 5 and 8, the hook 65 lying directly under the weft needle 50 and back of the eye 90 of said needle. Preferably the timing of the members 50 and 65 is so adjusted that the needle reaches the forward limit of its stroke and starts back before the hook quite reaches the path of the needle. A loop thus is 95 formed in the weft just under the needle and back of its eye and the hook passes through this loop into the position in which it is shown in Fig. 8. The hook then pauses while the needle continues on its return 100 stroke, thus carrying the part of the weft *w* that lies immediately below the eye of the needle against the shank of the hook and in front of the opening of the hook. The latch 96 at this time is held back in its open position by the pin 98, as clearly shown in Figs. 5 and 8. The hook 65 next starts on its return stroke and picks up the loop of the weft. Fig. 7 shows substantially the relative positions of the hook and needle shortly 110 after this step and while they both are making their return stroke.

During this time the yarn tension 58 is, of course, holding the weft *w* and when the needle 50 has withdrawn slightly but far enough to take up the slack in the weft, its further backward movement places sufficient tension on the weft lying in the shed to swing the hook 65 into the position in which it is shown in Fig. 7, any further swinging 115 movement, however, being limited by the stop 89. As the needle 50 continues on its backward stroke it tightens up the weft in the shed and draws more weft through the tension device 58, this weft feeding around the takeup roll 60 on the end of the needle and through the eye of the needle 50. In the meantime the hook 65 continues its backward stroke, arriving in the position in which it is shown in Fig. 9 where the latch 120

- 96 is closed by the loop which previously has been formed and encircles the shank of the hook. As the hook completes its backward movement, it pulls the loop of weft last formed through the loop encircling the shank of the hook, thus locking the latter loop against raveling. At substantially this time the harnesses change and the reed 20 swings back, beating up the pick just made.
- 10 This method of locking one loop by pulling another loop through it forms a series of chain stitches along the selvage edge of the fabric.

As soon as the reed has again returned to the position in which it is shown in Fig. 8, the needle 50 again advances carrying through the shed another double length of weft. The hook 65, having now interlocked the last pair of loops made, is swung slightly about the pivot 78 (see Fig. 4) by the spring 82 away from the selvage, thus carrying its point out of the path of the stitch last formed and thus avoiding any interference between the hook and the part of the selvage already completed. The movement of the hook 65 produced by the spring 92 takes place as soon as the hook has pulled the loop through the preceding loop far enough to leave any slack and usually begins as soon as the hook starts on its forward stroke. This movement of the hook maintains a tension on the loop that the hook now holds and pulls the loop into such a position that it cannot slip off the hook. This is a very important feature, particularly in the weaving of multi-ply goods where the loops of the several plies lie in different planes and in which there would be a tendency, if it were not for this movement, for the loop to slip off the hook when the hook begins its forward movement. The dropping of the loops in this manner also is prevented by positioning the hook so that its opening points away from the shed, thus making it necessary to have a longer or looser loop in order for it to slip off the hook than would be necessary if the opening in the hook pointed in any other direction. This loop, as it rides up on the thicker part of the shank above the opening of the hook, as shown in Fig. 4, swings the hook back toward the shed and guides it into the position in which it is shown in Fig. 5. As the loop slides back along the shank of the hook, it swings the latch 96 into its open position and then slides over the latch. This movement sometimes tends to snap the latch shut again after it has passed the loop but this action is prevented by the pressure of the pin 98 which lies directly in the path which the latch must take in making its closing movement. It is obvious that if the latch is closed while the hook is at the forward part of its stroke, where it is supposed to catch the

loop of weft last formed, this loop will 65 merely slide over the hook and this "pick" of weft will be missed. The pin 98 effectually prevents any action of this kind and thus facilitates the initial engagement between the hook and each loop of weft. 70

The cycle of operations above described is repeated so long as the machine continues in operation, each loop of weft as it is formed at the end of the shed opposite to that from which it is inserted being caught by the hook 65 and pulled through the loop previously formed. Sometimes there is a tendency, while the machine is running, to crowd the web of cloth toward the left hand end of the cloth beam 22, as it is shown in Figs. 1 80 and 3, and in order to resist this tendency the beam may be provided with a flange at this end, as shown in the drawings. This flange also backs up the fabric at the end or apex of the shed and facilitates the shedding 85 of the loops off the hook 65 as it interlocks one loop with another.

The motions of the different parts, and particularly those of the needle 50, the hook 65 and the reed 20 must be timed very accurately in order to produce satisfactory results, especially at high speeds. This has been one of the difficulties encountered in previous designs of needle looms. In the present machine this difficulty is overcome 90 by driving the weft inserting needle with a crank or an eccentric mechanism, and driving both the hook 65 and the reed with cams, these cams being designed to move their respective members in the proper timed relationship to the movement of the weft inserting needle 50. I regard it as essential to the successful operation of a machine of this character that either the needle 50 or the hook 65 be driven by a cam. 105

An important advantage of this machine is that all its operating parts may be run at relatively high speeds, thus permitting the production of the goods at a rate much higher than is possible with looms of the 110 character now available for this purpose. Furthermore, the fact that the machine locks the weft by knitting together the weft loops is an important advantage since it avoids the necessity for using a separate selvage 115 thread and thus avoids the stopping and annoyance attending the handling and renewal of a separate thread. The weft thread obviously can be supplied from spools or cones of very large size so that the interruptions of operation necessary to renew this thread are infrequent and such interruptions need only be very short. The machine also is adapted, with certain modifications, for use in weaving fabrics in which 120 a separate selvage thread is used to lock the weft against raveling. It is obvious that the machine is capable of manufacturing 125

either single or multi-ply goods. A fabric which the machine is especially designed to make is shown and described in a co-pending application assigned to the assignee of 5 the present invention.

Having thus described my invention, what I claim as new and desire to secure by Letters Patent of the United States is:—

1. In a needle loom, the combination with 10 warp holding and operating mechanism, of weft inserting means operative to lay a double length of weft in each shed of the warp, leaving a loop in the end of said length at the selvage edge of the fabric, a hook operative to pull each loop thus formed 15 through a preceding loop, means for operating said hook, a latch carried by said hook and movable relatively thereto to close or open the opening in the hook, and means 20 for holding said latch in its open position while the initial engagement between the hook and each loop is made.
2. In a needle loom, the combination with 25 warp holding and operating mechanism, of weft inserting means operative to lay a double length of weft in each shed of the warp, leaving a loop in the end of said length at the selvage edge of the fabric, a hook movable through each loop and operative to pull 30 each loop as it is formed through the preceding loop, and mechanism for operating said hook including means constructed and arranged to give it a loop tensioning movement as it advances.
3. In a needle loom, the combination with 35 a warp holding and operating mechanism, of weft inserting means operative to lay a double length of weft in each shed, leaving a loop in the end of said length at the selvage 40 edge of the fabric, a hook mounted for to and fro movement to enter each loop as it is formed, means for operating said hook to cause it to pull each loop as it is formed through the preceding loop and thus form 45 a series of chain stitches along one selvage edge of the fabric, and means for giving said hook a movement additional to said to and fro movement to prevent interference between said hook and stitches as the hook 50 advances.

4. In a needle loom, the combination with warp holding and operating mechanism including means for shedding the warp, of 55 weft inserting means operative to lay a double length of weft in each shed of the warp thus forming a loop in the end of each of said lengths at the selvage edge opposite to the side of the shed from which the weft is inserted, a hook mounted for 60 movement transversely to the direction in which said weft is inserted and operative to pull each loop so formed through a preceding loop, means for giving said hook its operative movement, and means operat-

ing on said hook to swing it yieldingly away 65 from the shed.

5. In a needle loom, the combination with 70 warp holding and operating mechanism including means for shedding the warp, of a reciprocating needle mounted for movement through the shed of the warp, means for 75 operating said needle, a hook mounted at the side of the shed opposite to that from which said needle is inserted and arranged to have a reciprocating movement from a point close to the path of said needle substantially to the apex of the shed, means for giving said hook its operative movement, said hook being mounted to swing toward and from the shed, a spring tending to 80 swing said hook away from the shed and means for limiting said swinging movement of the hook.

6. In a needle loom, the combination with 85 warp holding and operating mechanism including means for shedding the warp, of a weft inserting needle mounted to reciprocate through the shed of the warp, a hook mounted beside the shed for to and fro movement from a point close to the path 90 of said needle substantially to the apex of the shed, the opening in said hook pointing away from the shed, and operating mechanism for said hook.

7. In a needle loom, the combination with 95 warp holding and operating mechanism including means for shedding the warp, of a weft inserting needle mounted for reciprocating movement through the shed of the warp, a hook mounted at the side of the shed 100 opposite to that from which the needle is inserted and arranged to have a reciprocating movement from a point close to the path of said needle substantially to the apex of the shed, a latch carried by said hook and 105 movable to open or close the hook, operating means for said needle and hook including a cam arranged to drive one of said members in a timed relationship to the movements of the other member so that one of said members will pause while the movement of the other member effects an operative engagement between said hook and the weft carried by said needle, and means for holding 110 said latch in its open position while the initial engagement between said hook and the weft is made.

8. In a needle loom, the combination with 115 warp holding and operating mechanism including means for shedding the warp, of a reciprocating weft inserting needle mounted 120 for movement through the shed of the warp, an eccentric mechanism arranged to operate said needle, a hook mounted at the side of the shed opposite to that from which said 125 needle is inserted and arranged to have a reciprocating movement from a point close to the path of said needle substantially to

the apex of the shed, and a cam mechanism arranged to operate said hook and constructed to cause the hook to pause after advancing to a point adjacent to the path of 5 said needle while the movement of the needle effects an engagement with said hook of the weft carried by the needle.

In testimony whereof I have signed my name to this specification in the presence of two subscribing witnesses.

EDWIN E. WAITE.
